DESIGN.

T. G. HAWKES.

ORNAMENTATION OF GLASSWARE, &c.

No. 18,267.

Patented Apr. 24, 1888.

UNITED STATES PATENT OFFICE.

THOMAS G. HAWKES, OF CORNING, NEW YORK.

DESIGN FOR THE ORNAMENTATION OF GLASSWARE, &c.

SPECIFICATION forming part of Design No. 18,267, dated April 24, 1888.

Application filed January 9, 1888. Serial No. 260,230. Term of patent 7 years.

To all whom it may concern:

Be it known that I, THOMAS G. HAWKES, a citizen of the United States, residing at Corning, in the county of Steuben and State of New York, have invented and produced a new and original Design for the Ornamentation of Glass and other Ware, of which the following is a specification, reference being had to the accompanying photograph, forming part thereof.

10 I show my design applied as an ornament to a glass dish.

My design consists of intersecting arcs of circles 1, seven in number, arranged to form a seven-pointed star with triangular figures at the points. In the center of this star is formed a rosette, 2, while the triangular figures at the several points of the star are made with roughened surfaces 3. The portions of the arcs of the circle projecting beyond the star have be-

20 tween them ovate figures 4, obtuse at the outer ends, which in the present instance form part of the edge of the dish. Between these ovate figures, and extending from between the points of the star, are banner-like portions 5, the main body of which is made up of hexagonal and triangular figures 6, 7, and the outer edge of which has a fan-shaped figure, 8.

Having thus described my invention, the following is what I claim as new therein and desire to secure by Letters Patent:

30 The design for the ornamentation of glass and other ware, substantially as herein described and shown.

THOMAS G. HAWKES.
